UNITED STATES PATENT OFFICE.

FREDERICK G. KOLLENBERG, OF OWENSBORO, KENTUCKY, ASSIGNOR OF ONE-HALF TO
WILLIAM E. DANHAUER, OF OWENSBORO, KENTUCKY.

BOTTLE-CAP.

1,070,701.

Specification of Letters Patent. Patented Aug. 19, 1913.

Application filed February 26, 1913. Serial No. 750,892.

To all whom it may concern:

Be it known that I, FREDERICK G. KOLLENBERG, a citizen of the United States, residing at Owensboro, in the county of 5 Davies and State of Kentucky, have invented a new and useful Bottle-Cap, of which the following is a specification.

This invention relates to bottle caps, one of its objects being to provide a cap which 10 constitutes an efficient closure for the bottle, holding the stopper of the cap positively in position so that it cannot become unseated as the result of rough handling, climatic changes, etc.

15 A further object is to provide a cap which can be applied readily and which includes a hinged member and a bendable neck engaging member shiftable into position to fasten the hinged member in closed position and 20 also shiftable to release said hinged member so that it can be used as a hinged closure.

Another object is to provide a device of 25 this character which is cheap to manufacture and which can be readily placed in and removed from position.

With the foregoing and other objects in view which will appear as the description proceeds, the invention resides in the combination and arrangement of parts and in 30 the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

40 In said drawings:—Figure 1 is a plan view of a bottle having the present improvements in position thereon, the closure being shown secured in closed position. Fig. 2 is a section on line A—B Fig. 1. Fig. 3 is a section on line C—D Fig. 1. Fig. 4 is a plan view of the closure, the parts being shown separated. Fig. 5 is a side elevation of a portion of the ring.

45 Referring to the figures by characters of reference 1 designates a split ring which is U-shaped in cross section, the said ring being provided at equal distances from its ends with V-shaped incisions 2, these incisions being diametrically opposed so that 55 the split ring is thus sub-divided into a cen-

tral semi-circular portion 3 and end portions 4. A bendable tongue 5 extends from one of the end portions and is adapted to be inserted into a slot formed in the other end portion. The ring is so shaped and proportioned as to fit snugly around the mouth of a bottle and when thus positioned with the tongue 5 inserted through the slot 6 and bent back, the ring will not become displaced relative to the bottle. 60

A tongue 7 is formed at the center of the middle portion 3 preferably by cutting incisions in said portion from the inner edge of the top thereof as shown particularly in Fig. 4. This tongue 7 constitutes a hinge 70 member and extends through a slot 7' formed in a disk 8 preferably made of thin sheet metal. This disk has a central depression or recess 9 in the center of the lower face thereof and in which a cork 75 stopper 10 is glued or otherwise secured. As shown in the drawings, this stopper is preferably provided with a flange 11 extending therearound and adapted to rest upon the top of the bottle neck. 80

In applying the cap to a bottle, the tongue 7 is first inserted through the slot 7' and then bent back so as to form a hinge loop. The semi-circular portion 3 of the ring is then slid onto the neck of the bottle so as 85 to engage the rib surrounding the mouth thereof. The disk 8 is then swung downwardly so as to force the stopper 10 into the mouth of the bottle after which the end portions 4 of the ring are bent inwardly 90 against the bottle neck so that the top flanges of said end portions will lap the marginal portion of the disk 8 and hold said portion pressed toward the bottle neck, thus clamping the flange 11 of the cork tightly onto the 95 neck. As the end portions 4 are moved toward each other, the tongue 5 is brought into position where it can be inserted into the slot 6 and bent back, thus securely fastening the parts to the bottle. Obviously 100 with the stopper thus held in place, there is no danger of it becoming removed accidentally. When it is desired to use the contents of the bottle, the tongue 5 is removed from the slot 6 and the end portions 4 of the ring are bent outwardly. The disk 8 is then swung upwardly about its hinge so as to partly or entirely withdraw the stopper 10 from the neck whereupon the end portions 4 are again pressed back toward each other 110

and into engagement with the bottle neck and tongue 5 is inserted through slot 6 and bent back so as thus to fasten the ring to the bottle neck. When disk 8 is released it will 5 gravitate down onto the central and end portions 3 and 4 of the ring and stopper 10 can be forced into the neck of the bottle. Thus the bottle will remain closed until it is desired to remove a portion of its contents 10 whereupon the disk 8 can be swung upwardly, thus exposing the opening in the bottle neck.

It is to be understood that the cap herein described is particularly designed for use 15 in connection with ink bottles, although it is to be understood that it can be used wherever it is desired to employ a hinged cover which will be fastened securely in closed position after the bottle has received 20 its initial contents but which can be released and used as a hinged cover or cap by the purchaser.

What is claimed is:—

A bottle cap including a split ring shaped 25 transversely to embrace the annular rib upon

the mouth of a bottle neck, said ring having incisions dividing the ring into end portions and an intermediate portion, the said end portions being bendable at the points of incision relative to the intermediate portion, a 30 tongue formed with the intermediate portion, a disk adapted to rest upon said intermediate portion and to be lapped and retained by the end portions of the ring, said disk having an opening for the reception of 35 the tongue to form a hinge connection, a stopper carried by the disk and adapted to enter the mouth of a bottle to which the cap is applied, and a tongue extending from one of the end portions for entering an opening 40 in the opposed end portion to tie the ring about the mouth of a bottle neck.

In testimony that I claim the foregoing as my own, I have hereto affixed my signature in the presence of two witnesses.

FREDERICK G. KOLLENBERG.
